UNITED STATES PATENT OFFICE.

LOUIS H. ESSELMANN, OF ST. LOUIS, MISSOURI, ASSIGNOR OF ONE-HALF TO JOHN SHALHOUB, OF ST. LOUIS, MISSOURI.

PASTRY-CONE MACHINE.

1,419,622.

Specification of Letters Patent. Patented June 13, 1922.

Application filed June 13, 1920. Serial No. 389,982.

To all whom it may concern:

Be it known that I, LOUIS H. ESSELMANN, a citizen of the United States, residing at the city of St. Louis, in the State of Missouri, have invented certain new and useful Improvements in Pastry-Cone Machines, of which the following is a specification.

This invention relates to certain new and useful improvements in mold-closing and opening devices for pastry-forming machines. The object of this invention is to provide novel mechanism for automatically closing and locking the molds until the pastry within said molds has been cooked, and then unlocking said molds so that the cooked pastry may be removed therefrom. In the drawings, this invention is shown as applied to a machine for manufacturing pastry ice cream cones, but it must be understood that this invention may be employed equally well on other machines of this type.

In the accompanying drawings forming part of this specification, in which like numbers of reference denote like parts wherever they occur.

Figure 1 is a top plan view of an ice cream cone machine showing a practical application of this invention;

Figure 2 is a fragmental view of the locking device showing a mold in locked position;

Figure 3 is a top plan view of the locking device;

Figure 4 is a side elevation of the locking device shown applied to an ice cream cone machine;

Figure 5 is a detail of the locking link;

Figure 6 is a fragmental sectional view showing the manner in which the molds are unlocked preparatory to removing the cooked pastry;

Figure 7 is a top plan view of the unlocking device, and

Figure 8 is a side elevation of the unlocking device shown applied to an ice cream cone machine.

Referring more in detail to the drawings, it will be seen that in carrying out this invention, a large rotatably mounted gear wheel 1 is employed and upon this large rotatably mounted gear wheel 1 are provided a plurality of pastry molds or pans 2. These pans are of the type used in the manufacture of ice cream cones. Meshing with the gear wheel 1 is provided a pinion 3,

which is driven in the direction indicated by the arrow by any suitable means, such as an electric motor (not shown). This will cause rotation of the gear wheel 1 in a clockwise direction. The pans 2 are preferably composed of two members 4 and 5 (see Figure 4). The lower member 5 of each pan 2 is rigidly mounted upon the gear wheel 1, and the upper member 4 (which may be termed the lid) is pivotally mounted upon the member 5, as at 6. This allows the upper member 4 to be swung upwardly about the pivot 6 to permit the removal of the cooked pastry.

To raise the lids of the molds 2, vertical arms 7 are provided upon the inner ends of the said lids 4. These arms 7 terminate in stud shafts 8, on which are rotatably mounted rollers 9, which strike against and ride within cam 10. This cam opens the molds 2 in order that the cooked pastry may be removed and then permits automatic closing of said molds after they have been refilled with the uncooked batter, the lids 4 closing by gravity. The batter is fed into the molds 2 as they pass under a batter-feeding device 11 (described in Patent 1,303,218, dated May 6, 1919). After the lower members 5 of the molds 2 have received their charges of fresh batter, the cam 10 permits the upper members or lids 4 of the molds 2 to drop into partially closed position, shown at the right in Figure 4. The molds 2 then pass under a cooking hood 12, in which heat is applied to said molds by any suitable means, such as a gas burner (not shown). Closing mechanisms for tightly closing and locking the lids 4 of the molds 2 shortly after the said molds have entered the hood 12, consists of two rotatably mounted disks 13 and 14. These disks are rotatably mounted on spaced arbors 15 and 16, said arbors being rigidly mounted on an upstanding bracket 17. Stationary collars 18 prevent any horizontal movement of the disks 13 and 14, along the center lines of their respective arbors 15 and 16. The outer ends of the mold members 4 and 5 project to form arms 19 and 20. Upon the upper arm 19 is mounted a friction-reducing roller 21, and upon the lower arm 20 is provided a locking link 22 pivotally mounted at 23. This link 23 is provided at one end with a loop 24 adapted to receive an extension 25 of the arm 19. As the molds rotate, the roller 21 on the arm 19 strikes the periphery of the disk 13 below the center 110

line of said disk. As the molds 2 continue their travel, the roller 21 travels on the periphery of the disk 13 to its lowermost point, as shown in Figure 2. During this operation, the arm 20 strikes and is supported by the disk 14. This relieves the arm 20 of the strain caused by the downward movement of the lid 4 on the mold 2. The arms 19 and 20 are locked in this closed position by the link 22 in a manner hereinafter described.

In order to move the locking links 22 to operative position I have provided an annular track 26 surrounding the gear wheel 1 and at a slight distance therefrom, as shown in the drawings. When the molds 2 are unlocked, the links 22 ride around on the track 26 in an inclined position, as shown in Figure 4. Upon this track 26 at the point where the lids 4 of the molds 2 are completely closed by the disks 13 and 14, the shoulder or projection 27 forces the top 24 of the locking links 22 over the projection 25 on the arms 19. This effectually locks the lids 4 of the molds 2 in a closed position. The molds 2 continue on under the hood 12 until the pastry in the pans is thoroughly cooked.

After the pastry is thoroughly cooked, the molds must be unlocked, so that the cooked pastry may be removed therefrom. To accomplish this, the depending wedge-shaped arm 28 carried by the supporting framework of the machine, is so placed that the point of said arm 28 forces its way between the rollers 21 of the arms 19 and the upper end 24 of the links 22, thereby forcing the links 22 off the arms 19 as shown in Figure 7. The unlocked molds 2 then pass on from under the hood and are opened by the cam 10 operating against the rollers 9 of the mold lids 4. The cooked pastry may then be removed by an attendant, and the operation of the machine repeated.

While the preferred embodiment of the invention has been shown and described, it is to be understood that minor changes in the details of construction and arrangement of parts may be resorted to within the scope of what is claimed, without departing from the spirit of the invention.

Having thus described this invention, I hereby reserve the benefit of all changes in form, arrangement, order, or use of parts, as it is evident that many minor changes may be made therein without departing from the spirit of this invention or the scope of the following claims.

I claim:

1. In a mold structure, complementary mold members, one of said mold members being pivoted to the remaining mold member, extensions on the outer end of said mold members, rollers carried by the extensions of one mold member, latching members carried by said extensions of the remaining mold member, means for engagement with said rollers and the extensions opposite the same to force said extensions toward one another, means for swinging said latching members into engagement with the roller carrying extensions to lock together said mold members, 65 means for automatically releasing said latching members at times, to permit opening of said mold members, and means for opening said mold members.

2. In a mold structure, complementary mold members, one of said mold members being pivoted to the remaining mold member, extensions on the outer end of said mold members, rollers carried by the extensions of one mold member, latching members carried by said extensions of the remaining mold member, means for engagement with said rollers and the extensions opposite the same to force said extensions toward one another, means for swinging said latching members into engagement with the roller carrying extensions to lock together said mold members, means for automatically releasing said latching members at times, to permit opening of said mold members, means for opening said mold members, supporting means for said mold members, and means to revolve said mold members on said supporting means.

In testimony whereof I hereunto affix my signature.

LOUIS H. ESSELMANN.
